CLAIM

We claim the ornamental design for a bottle, as shown and described.

DESCRIPTION

FIG. 1 is a perspective view of our new design.

FIG. 2 is a top plan view thereof.

FIG. 3 is a front view thereof.

FIG. 4 is a left side view thereof.

FIG. 5 is a rear view thereof.

FIG. 6 is a right side view thereof; and,

FIG. 7 is a bottom plan view thereof.

(Continued)

The broken lines in the drawings illustrate portions of the bottle that form no part of the claim.

1 Claim, 3 Drawing Sheets
